DESIGN FOR A HOUSING FOR A SIGNAL DEVICE

Lloyd Rittenhouse, Honeoye Falls, N. Y., assignor
to The A. E. Rittenhouse Co., Inc., Honeoye
Falls, N. Y., a corporation of New York

Application November 30, 1936, Serial No. 66,208

Term of patent 14 years

To all whom it may concern:

Be it known that I, Lloyd Rittenhouse, a citizen
of the United States of America, residing at
Honeoye Falls, in the county of Monroe and
State of New York, have invented a new, original,
and ornamental Design for a Housing for a Signal
Device, of which the following is a specification,
reference being had to the accompanying draw-
ing forming a part thereof.

In the drawing:

Fig. 1 is a front elevation of a housing for a
signal device, showing my new design, and

Fig. 2 is a plan view of the same.

I claim:

The ornamental design for a housing for a sig-
nal device, as shown.

LLOYD RITTENHOUSE.
